UNITED STATES PATENT OFFICE.

MOSES GRAHAM, OF PHILADELPHIA, PENNSYLVANIA.

MILK-BOTTLE LOCK.

1,042,550.

Specification of Letters Patent.

Patented Oct. 29, 1912.

Application filed April 20, 1912. Serial No. 692,043

To all whom it may concern:

Be it known that I, MOSES GRAHAM, a citizen of the United States, residing at Philadelphia, in the county of Philadelphia and State of Pennsylvania, have invented 5 certain new and useful Improvements in Milk-Bottle Locks, of which the following is a specification.

My invention relates to improvements in 10 milk bottle locks, the object of the invention being to provide a device of this kind which is adapted to be secured to the frame of a door, and which enables the milkman to readily position the bottle in the device, 15 but which will prevent any removal of the bottle except by turning the same inwardly toward the door, such movement being prevented by the door when in closed position, hence only the occupant of the house can 20 release the bottle by first opening the door.

A further object is to provide a device of this character which is of extremely simple inexpensive construction, strong and durable in use.

25 With these and other objects in view, the invention consists in certain novel features of construction and combinations and arrangements of parts, as will be more fully hereinafter described and pointed out in 30 the claims.

In the accompanying drawings: Figure 1, is a perspective view illustrating my improvements. Fig. 2, is a view in elevation of the lock. Fig. 3, is a view in elevation 35 of the base plate with the outer casing removed. Fig. 4, is a view in elevation of the locking pawl. Fig. 5, is a view in elevation of the inner face of the casing, and Fig. 6, is a fragmentary view in section on 40 the line 6—6 of Fig. 2.

1, represents the door, and 2 the door frame. My improved bottle lock is secured 45 to the door frame, and comprises a base plate 3 of general circular form having screw-receiving perforated extensions 4 to secure the device to the frame. The base plate 3 is made with a circular flange 5 concentric with a central integral stud 6. This stud 6 projects through a central opening 7 in a circular casing 8, and the latter is of an external diameter to lie within the flange 5.

50 Casing 8 is mounted to turn on the stud 6, and is secured against removal by means of a locking pin 9. The casing 8 supports a bottle clamp consisting of a fixed arm 10,

and a pivoted arm 11, both curved and adapted to fit snugly around the neck of an ordinary milk bottle 12. The arm 10 is preferably integral with casing 8, but may 60 of course be fixed thereto in other ways.

Arm 11 projects through a slot 12 in the casing 8, and at its inner end is made with integral trunnions 13 pivotally supported in bearing brackets 14, the latter integral with 65 casing 8 and located at opposite sides of the slot 12. This pivoted arm 11 is provided with a shoulder 15 which is adapted to ride over the outer face of a concentric curved flange 16 integral with base plate 3, 70 and having beveled or inclined ends 17. This flange 16 limits the pivotal movement of the arm 11 sufficiently to prevent the milk bottle from being released, but when the casing 8 is turned, so that the shoulder 15 75 is in any other position, arm 11 may be swung backwardly to allow the bottle to be released or inserted.

On the inner face of casing 8, integral 80 brackets 18 are provided and constitute bearings for the integral journal 19 of a pawl 20. This pawl 20 has a tooth 21 which is adapted to project through an opening 22 in base plate 3, and prevent the rotation of 85 the casing in one direction as will now be explained.

When the lock is empty, it may be readily 90 revolved so that when the milkman arrives with the bottle of milk, he may turn the casing 8 and move the pivoted jaw 11 so as to readily position the bottle neck between the jaws 10 and 11. He then turns the bottle 95 downwardly to an upright position. This movement of the casing brings the lock to the position shown in Figs. 2 and 6, but in this position the arm 11 is held against pivotal movement by the flange 16 and the shoulder 21 of pawl 20, projects into the opening 22, and prevents any turning movement of the casing in a direction to swing 100 the bottle outwardly. The bottle can, however, be swung inwardly, but not far enough to move the shoulder 15 off of flange 16, because the door 1 when in closed position 105 will prevent this movement. The bottle is therefore securely locked until the door 1 is swung out of the way, when the bottle may be swung inwardly and upwardly, moving the shoulder 15 off of flange 16 and allowing the arm 11 to fall and release the 110 bottle. It will therefore be noted, that while my improvements permit rotary movement

in one direction, this rotary movement is prevented by the bottle engaging the door when the door is closed. It is therefore simply necessary to open the door to release the bottle, and the bottle can be released in no other way. The pawl 20 is so positioned with relation to its journal 19 that the center of gravity is to one side of this journal, and the shoulder 21 will, by the weight of the pawl, swing into the opening 22, thus dispensing with the necessity for any spring for the purpose.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A device of the character described, comprising a base plate, a casing mounted to turn on the base plate, a fixed arm on the casing, a pivoted arm supported by the casing, a flange on the plate, and a shoulder on the pivoted arm adapted to be positioned over the flange and limit the movement of the pivoted arm when in locking position, substantially as described.

2. A device of the character described, comprising a base plate, a casing mounted to turn on the base plate, a fixed arm on the casing, a pivoted arm supported by the casing, means within the casing controlling the pivotal movement of the pivoted arm, and a pivoted pawl carried by the casing and constructed to lock with the plate holding the casing against rotary movement in one direction, substantially as described.

3. A device of the character described, comprising a base plate, a casing mounted to turn on the base plate, a fixed arm on the casing, a pivoted arm supported by the casing, a flange on the plate, a shoulder on the pivoted arm adapted to be positioned over the flange and limit the movement of the pivoted arm when in locking position, and a pivoted pawl carried by the casing and constructed to lock with the plate holding the casing against rotary movement in one direction, substantially as described.

4. A device of the character described, comprising a base plate, a circular flange on the base plate, a central journal on the base plate, a casing mounted to turn on the journal and having its edges confined within the

flange, a fixed arm on the casing, a pivoted arm on the casing, and means holding the pivoted arm against movement when the casing is in locking position, substantially as described.

5. A device of the character described, comprising a base plate, a circular flange on the base plate, a central journal on the base plate, a casing mounted to turn on the journal and having its edges confined within the flange, a fixed arm on the casing, a pivoted arm on the casing, a curved flange on the base plate, and a shoulder on the pivoted arm adapted to be positioned over said flange and limit the movement of the pivotal arm when the casing is in locking position, substantially as described.

6. A device of the character described, comprising a base plate, a circular flange on the base plate, a central journal on the base plate, a casing mounted to turn on the journal and having its edges confined within the flange, a fixed arm on the casing, a pivoted arm on the casing, means holding the pivoted arm against movement when the casing is in locking position, brackets integral with the casing, a pawl pivotally supported in the brackets, said base plate having an opening therein, and said pawl having a shoulder thereon adapted to move into the opening and prevent the turning movement of the casing in one direction, substantially as described.

7. A device of the character described, comprising a base plate, a circular flange on the base plate, a central journal on the base plate, a casing mounted to turn on the journal and having its edges confined within the flange, a fixed arm on the casing, a pivoted arm on the casing, a curved flange on the base plate, a shoulder on the pivoted arm adapted to be positioned over said flange and limit the movement of the pivotal arm when the casing is in locking position, brackets integral with the casing, a pawl pivotally supported in the brackets, said base plate having an opening therein, and said pawl having a shoulder thereon adapted to move into the opening and prevent the turning movement of the casing in one direction, substantially as described.

In testimony whereof I have signed my name to this specification in the presence of two subscribing witnesses.

MOSES GRAHAM.
